UNITED STATES PATENT OFFICE.

EARL A. HECHT, OF MANSFIELD, OHIO.

DESIGN FOR A TIRE TREAD.

60,724.

Specification for Design.

Patented Mar. 28, 1922.

Application filed September 2, 1921. Serial No. 498,127. Term of patent 14 years.

To all whom it may concern:

Be it known that I, EARL A. HECHT, residing at Mansfield, in the county of Richland and State of Ohio, a citizen of the United States of America, have invented a new, original, and ornamental Design for a Tire Tread, of which the following is a specification, reference being had to the accompanying drawing, forming a part thereof.

Fig. 1, is an elevation of a section of the periphery of the tire.

Fig. 2, is a cross section of the tire on the line 1—1, at the ends of the line shown drawn across Fig. 1 on the drawing.

I claim—

The ornamental design for a tire tread as shown.

EARL A. HECHT.

In the presence of—

JOHN H. CROSS,
RUTH SNYDER.
